CLAIM

The ornamental design for a kabob skewer, as shown and described.

DESCRIPTION

FIG. 1 is a top and bottom plan view, wherein the bottom plan view is a mirror image thereof of the top view, of the handle end of the kabob skewer;

FIG. 2 is a right side and left side elevation, wherein the left side elevation is a mirror image thereof of the right side elevation, of the handle end of the kabob skewer;

FIG. 3 is a perspective view of the handle end of the kabob skewer;

FIG. 4 is a top and bottom plan view, wherein the bottom plan view is a mirror image thereof of the top view, of the tip end of a long kabob skewer;

FIG. 5 is a right side and left side elevation, wherein the left side elevation is a mirror image thereof of the right side elevation, of the tip end of a long kabob skewer;

FIG. 6 is a perspective view of the tip end of a long kabob skewer;

FIG. 7 is a front view from the tip end of the kabob skewer;

FIG. 8 is a rear view from the handle end of the kabob skewer;

FIG. 9 is a right side and left side perspective view, wherein the left side perspective is a mirror image thereof of the right side perspective, of a long kabob skewer; and,

FIG. 10 is a right side and left side perspective view, wherein the left side perspective is a mirror image thereof of the right side perspective, of a short kabob skewer.

The dotted lines are for purposes of illustrating a use and form no part of the claimed design.
